UNITED STATES PATENT OFFICE

WILLIAM T. GUTH, OF BROOKLYN, NEW YORK

DESIGN FOR A MOTOR VEHICLE FENDER

Application filed November 9, 1931. Serial No. 41,670. Term of patent 14 years.

To all whom it may concern:

Be it known that I, WILLIAM T. GUTH, a citizen of the United States, residing in Brooklyn, county of Kings, and State of New York, have invented a new, original, and ornamental Design for a Motor Vehicle Fender, of which the following is a specification, reference being had to the accompanying drawings, forming a part thereof.

In the drawings:

Figure 1 is a side elevation of the motor vehicle fender;

Figure 2 is a plan view of the same; and

Figure 3 is a front elevation of the same.

A salient feature of the invention consists in imparting an appearance of massiveness to the fenders by providing a continuous

heavy front flange at the front of the fender from the base to the outer extremity thereof. A further feature resides in the provision of a series of light apertures in the upper portion of the flange referred to through which a light mounted underneath the fender may shine.

The present application is a continuation in part of my pending application Serial No. D.38,964, filed March 6, 1931, for motor vehicle fender.

I claim:

The ornamental design for a motor vehicle fender substantially as shown and described herein.

WILLIAM T. GUTH.
